UNITED STATES PATENT OFFICE.

JACOB AISENBERG, OF CORONA, NEW YORK.

MOVING SIGN.

1,387,635.

Specification of Letters Patent. Patented Aug. 16, 1921.

Application filed September 10, 1919. Serial No. 322,838.

To all whom it may concern:

Be it known that I, JACOB AISENBERG, a citizen of the United States, and a resident of Corona, Long Island, in the county of 5 Queens, State of New York, have invented an Improvement in Moving Signs, of which the following is a specification.

This invention relates to exhibiting apparatus.

10 Further it relates to advertising devices of the moving type.

Further it relates to the so-called moving signs.

15 More particularly it relates to the method and apparatus of providing advertisements which attract the eye of the observer.

The drawings attached hereto are of a selected preferred embodiment of the invention wherein,

20 Figure 1 is a general view of the exhibiting device,

Fig. 2 is a view of the device partly broken away and partly in section,

Fig. 3 is a top plan view of the device,

25 Fig. 4 is a section in part taken on the lines 4—4 of Fig. 3,

Fig. 5 is a detailed view of the supporting means,

30 Fig. 6 is an elevation view of means for attaching individual characters to one another,

Fig. 7 is a section of Fig. 6.

One of the general principles in successful advertising is to exhibit some object 35 or some statement which will catch the eye of the casual observer and will cause him to further investigate. In producing apparatus which may be used for exhibiting purposes, it is highly essential to produce an apparatus which is small and compact and may, therefore, be used in show windows as one of the many places in which such an apparatus may be placed.

40 This invention is directed to an exhibiting apparatus and the selected embodiment of such an apparatus as hereinafter described is of the type which presents moving words, phrases or illustrations. This preferred embodiment permits of expansion and 45 may be manufactured to furnish any particular size of characters, letters, figures or illustrations and to permit the use of phrases and clauses of different lengths and of varied sayings.

55 Referring to the drawings, in Fig. 1 the face of a container 1 is shown as having an

opening 2 wherein individual character groups may pass from one end of the opening to the other. In this figure, it is noted that the characters exhibited are individually formed and are attached to one another and are combined to spell the word "Advertise." Any words, figures or illustrations may be grouped together to form any particular phrase, saying or illustration. Blank portions are employed to form spaces between any two groups of characters, as shown by the blank strips at each end of the word "Advertise."

60 The individual characters 3 in this embodiment of the device are partially transparent so that illuminating means placed in the rear of a row of characters will make them more easily read. These characters are made of a flexible material which is transparent; 65 linen has been successfully employed for this purpose; however, any other suitable material may be used. Characters, figures or illustrations may be formed on this material by rendering parts of it opaque. Two or 70 more colors may be employed to set out the characters. If desired a light may be thrown on the front of the container 1 to light the characters as they pass before the opening 2. The illumination is here shown as being in 75 the rear of the characters and is designated as electric bulbs 5, having the electric connections 6, and there may be as many of these 80 bulbs as desired; however, any form of illumination may be employed. Partition 7 having its inner surface a reflecting surface is used to assist in illuminating the characters as they pass the opening. Individual characters may be grouped together and are supported and carried by means of tapes 8 and 85 9 which run on rollers 10. One or more of these rollers may act as driving rollers and in this case the rollers 11 and 12 are the driving rollers operated by an electric motor 13 90 through reduction gears 14, if such gears are required. The driving means is not restricted to an electric motor and any other means may be adopted. The motor may be on the same circuit as the electric illuminating lamps or may be on a separate circuit so 95 that the illuminating means may be flashed on and off.

100 Referring to Fig. 3, a circuitous route for the characters is shown as being around the pulleys 11, 12, etc., and the path of the tapes carrying the characters is the same, and the 105 tapes move continuous from the roller 15 110

around the rollers 16, 17 and 18. The route around rollers 15, 16, 17 and 18 allows an interrupted path for the characters around three sides of the container and if desired 5 these may be exhibiting sides, any desired illuminating means for the additional sides may be employed.

The number of rollers may be increased and the width of the container may be increased 10 so that various length phrases and sayings may be included. The flexible tapes which support the characters expand and contract and in order to keep them taut at all times, roller 19 is mounted so that it moves 15 back and forth. This roller is carried in frame 20 attached to another frame 21 which moves backward guided by slots 22. The spring 23 having one end attached to the container 1 and the other end attached 20 to frame 21, tends to pull the roller toward the container and in this way the tapes are maintained taut.

The characters 3 which are exhibited and which are grouped together to form various 25 words, phrases or sayings, may have one or more characters thereon. In this case there is illustrated one character but it is to be understood that the use of one or more characters is within the scope of this invention. 30 Certain of these flexible members are totally opaque so that the illuminant does not show between groups of characters. In order to keep the transparent material from being folded and thereby obliterating the characters 35 thereon, supporting members 24 are placed on the edges of the material and extend beyond the edge to form holding portions to contact with tapes 8 and 9. The method of attachment is immaterial but it 40 has been found that placing the material on a supporting member of metal and then turning the metal over on itself has been very successful. By this method a double end of the metal is formed so that it will 45 slip over either side of the tapes 8 and 9 and will hold the character firmly in position on the tapes. Other means for maintaining the holding portions in contact with the tapes will be apparent to those 50 skilled in the art. Means are provided in the metal edges for attaching the next successive character by forming openings 25 and having the hooks 26 inserted and squeezed in position as shown at 27 in Fig. 55 7. For purposes of uniformity, one edge of a character carries the hooks held firmly in the holes 25 while the other edge simply has the holes to receive the free ends of the hooks. This means of attaching one figure 60 to another is not to be considered as being limited to the particular description but any well-known attaching means may be employed.

In order that the characters will not have 65 relative motion in respect to the tapes, some

of the supports may have edges with projections thereon as shown at 28. These projections are adapted to enter the tapes 8 and 9 to prevent any great relative movement therebetween. As a matter of convenience, 70 the blanks 4 generally have one of their supports with these projections.

Any general form of roller may be employed to receive the tapes and the ends of the supports of the characters so long as the 75 tapes are not permitted to move too great a distance apart and so long as the hooks are not squeezed in passing around the rollers. For purposes of describing and illustrating one form of roller and its various component 80 parts reference is made to Fig. 4 wherein a shaft 28' is shown carrying collars 29 and 30 which have flaring portions 31. The tapes are prevented from moving too far apart by means of these flaring portions, and 85 the hooks joining one character to another do not contact with any part of the roller while the supports are contacting with the collars. The rollers may be made of wood and in turning them from the sticks there 90 should be portions of large diameters to correspond to the flares 31 and there should be portions of small diameters to allow the hooks to pass around the rollers without being squeezed. When the distance between 95 the rollers is great, any form of channel may be employed to allow the lower tape and the edges of the metal supports to move therein and be supported so that the characters will not sag when moving between rollers. Such 100 supports may be used throughout the machine where desired.

The apparatus herein described and illustrated being one embodiment of the invention, permits advertising by means of words, 105 phrases, sayings and illustrations. It is possible with this device to change the characters or parts thereof without its becoming necessary to form an entirely new word reel. Since the characters are made of the 110 flexible material or formed on flexible material, this device has been made of much smaller dimensions, and, therefore, much more desirable as the size of the apparatus is not the noticeable feature; the words, 115 phrases, and characters employed then become the noticed features.

The container may be of such form that it may be disassembled and only the frame for supporting rollers, etc., will remain. 120 The container, however, as a unit or sections thereof, may have openings for ventilating purposes or for other purposes, and these openings may be guarded so that foreign material and the weather elements do not 125 enter it.

The apparatus herein described shows the letters or groups of letters moving from left to right and in a horizontal opening, it is to be understood that letters may follow each 130

other and be exhibited in openings other than horizontal.

It is to be understood that certain designs have been included and described but that 5 there may be modifications of the same and such modifications are considered as being within the scope of this invention.

I claim:

1. In an exhibiting apparatus, the combination of transparent flexible members having characters formed thereon, said members adapted to have relative movement with the frame of said apparatus, and supporting means for said members attached to the edge 15 thereof and exceeding the length of the edge to which attached for holding purposes.

2. In an exhibiting apparatus, the combination of a container having an opening therein, flexible strips having characters 20 thereon passing near said opening, metal edges on the longest sides of each of said strips and extending beyond said strips, one of said metal edges having the extending parts provided with projections, flexible 25 means for receiving and guiding said metal edges, and means for attaching one flexible strip to another.

3. In an exhibiting apparatus, the combination of a container having an opening therein, flexible characters passing near said opening, metal support engaging and extending beyond the edge of said flexible character, said extending portion provided with projections, and flexible tapes moving within 30 said apparatus and having engagement with said metal support.

4. In an exhibiting apparatus, the combination of a container having an opening therein, flexible characters for passing near said opening, flexible tapes moving in a circuitous route for carrying said characters and rollers for supporting and guiding said tapes, a slidable frame for holding one of 40 said rollers, said frame slidable in said container, and a resilient member connected to 45 the outer frame of said container and to said slidable frame for maintaining said frame near the outer edge of said container to keep said flexible tapes taut.

In testimony whereof I have signed my 50 name to this specification this 8th day of September, 1919.

JACOB AISENBERG.
